(57) **CLAIM**

The ornamental design for a pressure sensor, as shown and described.

DESCRIPTION

FIG. 1 is a top perspective view of the pressure sensor
FIG. 2 is a side elevational view of the pressure sensor
FIG. 3 is another side elevational view of the pressure sensor
FIG. 4 is a front elevational view of the pressure sensor
FIG. 5 is a back elevational view of the pressure sensor
FIG. 6 is a top view of the pressure sensor; and,
FIG. 7 is a bottom view of the pressure sensor.
The pressure sensor of the present invention is particularly
useful for the measurement of head pressure in bioreactors.
